WINDOW

Gustav R. Carl, Chicago, Ill., assignor of one-half
to Nicholas H. Bode, Chicago, Ill.

Application April 15, 1943, Serial No. 483,089

7 Claims. (Cl. 20—42)

This invention relates to sliding windows, preferably of the double hung type, and is particularly directed to means for permitting the sash to be swung inwardly to permit ready clearing of the same and to provide for swinging adjustment to permit ventilation.

The objects of the invention are to provide an improved window of the character set forth having novel actuating and controlling or stopping means; to provide a window having one or more slideable sash with means for controlling and guiding the sash to swing the same from vertical position and to hold the same in adjusted positions; to provide novel weather strip means for such windows; and to provide such other advantages and improvements as will appear more fully from the following description.

As shown in the accompanying drawings:

Figure 1 is a front or inside view of the window with the sash shown in adjusted positions in dotted lines;

Figure 2 is an enlarged vertical sectional view;

Figure 3 is a view similar to Figure 2 showing the sash in different adjusted positions;

Figure 4 is a sectional detail illustrating parts for supporting and controlling the lower sash;

Figure 5 is a sectional view taken on the line 5—5 of Figure 4 showing a portion of the sash;

Figure 6 is a view similar to Figure 4 showing the slide and supporting means for the upper sash;

Figure 7 is a sectional view taken on the line 7—7 of Figure 6 and showing a portion of the upper sash;

Figure 8 is a horizontal sectional detail showing parts on an enlarged scale;

Figure 9 is another horizontal sectional detail similar to Figure 8;

Figures 10, 11, 12 and 13 are perspective views of certain fastening or guiding members;

Figure 14 is an enlarged detail illustrating the holding or fastening means for the lower sash;

Figure 15 is a perspective view showing a portion of the sash supporting and guiding means and also the arrangement of the weather strips; and

Figure 16 is an enlarged detail illustrating the means for fastening the upper sash in its pivotal supports when the sash is swung inwardly out of sliding position.

As shown in these drawings the window frame or casement 15 is provided with sides or stiles 16, stool or sill 17 and top 18. The lower sash 19 is provided with pivots or trunnions 20 as shown particularly in Figure 11. These trunnions comprise strap portions 21 which are secured to the sides of the sash by screws or the like and round

bearing portions 22 which fit in grooves 23 in the sides of the frame, these grooves being formed by frame strips 24 and parting strips 25 as shown particularly in Figure 9. The parting strips are preferably provided with tongues 26 which engage with grooves 27 in the stiles 16 in order to make tight closures. The round or pivotal portions 22 are at all times in engagement with the grooves and provide guides for guiding the lower portions of the sash during its vertical movement and also pivots for swinging the sash, it being understood that the sash will swing freely between the frame strips 24.

The sides of the lower sash 19 are also provided with weather strips 28 in slideable relation therewith, preferably of the cross section shown in Figure 9. One portion of this strip is of substantially channel or U-shape having legs 29 and 30, the latter engaging with grooves in the sides of the sash. This strip also has a blade 31 which forms with the channel shape portion a groove 32 for receiving and coacting with one leg 33 of a fixed weather strip 34 of channel shape or U-shape section which embraces the blade 31 so that a substantially double joint is made between the weather strip members and the arrangement is also such that these members will remain in relative positions so as to close in a jack-knife fashion as will appear later.

The lower sash slides in the weather strip 28 when the sash is to be moved vertically but the sash and weather strip remain in relatively fixed positions when the sash is to be swung.

The weather strips 28 and 34 are connected at a short distance from their lower ends by means of links 35, the outer ends of these links providing pivots or fulcrums 36 which coact with the other parts to cause the lower edge of the sash or pivots 22 to move upwardly when the sash is to be swung to open position as shown in Figure 2.

The lower sash is counterbalanced by any suitable means such as counterweights or spring balances which are connected with ribbons or cords 37 as shown particularly in Figures 4 and 5. The lower ends of these ribbons are provided with rings 38 which engage with hooks 39 on slides or carriages 40 which engage with the grooves 23 in the frame and move longitudinally therein. Links 41 are pivoted at their upper ends by means of rivets 42 to the slides or carriages 40 and are pivoted at their lower ends to the sides of the sash by means of pivots 43.

When the lower sash is in its sliding position the counter-balance will act in the usual manner to control the vertical movement of the sash.

When the lower sash is to be swung downwardly or to cleaning position the links 41 coact with the counter-balance means to balance the opening or swinging movement. At the same time the links 35 will swing outwardly and when in their outermost positions their outer ends serve as fulcrums to cause the lower edge of the sash to move upwardly and out of contact with the stile or so that it is free to clear the stile and permit such swing movement of the sash. When the window is swung back to normal position the links 41 are again folded back against the sash and are in position to balance the vertical movement thereof. At the same time the links 35 are folded back between the weather strip members 28 and 33 and hold the members 28 against vertical movement. Thereupon the sash moves vertically in the weather strips 28 which serve as guides therefor.

The sash is held or controlled in its sliding and swinging movements by novel means which will now be described. Brackets or bearing blocks 44 are set in recesses in the frame strips 24 and provide substantial continuations of such strips. These blocks have transverse slots or grooves 45 to permit the passage of pins 46 which extend laterally from the sides of the sash, these pins being secured to the sash rails by integrally formed straps 47 as shown in Figure 10. When the sash is in normal or sliding position these pins move in the slots 23 in the sides of the frame and engage with the inner edges of the frame strips 24 to guide the sash in its vertical movement.

In order to prevent the pins from moving out through the grooves 45 during the sliding movement, keepers or guide members 48 are slidably mounted in the blocks 44 as shown in Figure 12, and have end portions 49 at right angles thereto for closing the inner ends of the grooves 45 or to make continuous guideways for the pins 46. These keepers are urged toward inner position by means of springs 50 which are interposed between projections 51 on the keepers and suitable abutments on the blocks. They are provided with handles 52 for drawing them out or to adjusted positions.

These keepers are held in adjusted positions by means of latches 53 which are pivoted at 54 to the blocks 44 and which have handles or projections 55 for swinging the same. These catches engage with grooves 56 and 57 in the bar portions of the keepers 48. The sides of the latches 53 are also preferably notched as shown at 58 for engagement with the grooved portions of the keepers.

When the lower sash is set for sliding the keepers 48 are pulled out and the latches 53 are swung up to engage with the outer grooves 57 and hold the keepers in their outer or projected positions. When in such positions the lugs or projections 49 close the inner ends of the openings 45 as indicated in dotted lines in Figure 14 and the lower sash will slide freely in its ordinary manner.

When it is desired to swing the lower sash inwardly as for cleaning as shown in Figure 2, the latches 53 are swung downwardly and out of engagement with the keepers 48 so that the inner ends of the keepers project into the grooves 23 and within the paths of the pins 46 and thus prevent their upward movement. By drawing out on the top of the sash these pins pass out through the openings 45 and the sash is swung down as above indicated.

If it is desired to fasten the lower sash in partly

opened position as for ventilation, the pins 46 are moved into position in the openings 45 and may be brought to rest in notches 59 in the lower wall of the grooves 45 and the latches 53 are again swung up into engagement with the keepers 48 and enter the inner grooves 56 and thus hold the keepers against longitudinal movement. At the same time the latches close the inner ends of the grooves or passageways 45 and thus the pins 46 will be held in the grooves while permitting limited movement of the upper edge of the sash for holding the same in the position shown in Figure 3.

The upper sash 60 is guided and held in its uppermost or closed position by combined fixed weather strips and guideways 61, preferably of substantially the cross section shown particularly in Figure 8. These weather strips have channel shaped portions with legs 62 which engage with slots 63 in the sides of the sash and preferably have plates or back portions 64 which engage with the parting strips 25 and have flanges or ribs 65 which fit tightly in grooves in the strips as shown. This construction makes a particularly weather-proof arrangement and prevents any air or wind from passing between the sash. The fixed guide members 61 terminate at approximately the center of the window frame or at the bottom of the top sash when it is in raised position. Somewhat similar combined weather strips, guideways, and pivotal supports 66 extend, when in normal position, from the lower ends of the guideways 61 to points adjacent to the lower portion of the frame where they are pivoted on pivots 67 to longitudinal metallic strips 68 which are fastened to the parting strips as shown in Figure 9 and have ribs extending into the strips to make tight closures therewith. The guide members 66 are also channel shaped in cross section and have legs 69 which engage with the slots 63 in the sides of the upper sash when it is slid downwardly. These guideways have stops or projections 70 adjacent to the pivots 67 for limiting the downward movement of the sash, the arrangement being such that when the sash engages with said stops the upper edge will be substantially in alignment with the tops of the guide members 66, and freed from the fixed upper guide members so that the sash may be swung inwardly or to cleaning position by swinging the sash and the guideways therewith on the pivots 67.

The upper sash is also counterbalanced by means of any suitable weight or spring counterbalances which have supporting cords or ribbons 71 which extend from the frame or box in the usual manner. The lower ends of the ribbons 71 are secured to slides 72 which engage with vertical grooves or guideways 73 in the sides of the frame in order to guide or support them in their vertical movement. Links 74 are pivoted at 75 to the slides 72 and are pivoted at their opposite or lower ends to the sides of the sash 60 by means of pivots 76.

In order to lock the sash 60 in the supporting member 66, or to prevent sliding of the sash out of such guideways when in lowered position, the ends of the links 74 extend a short distance beyond the pivots 76 and are adapted to engage with slots 77 in the legs of the guide members 66 as shown in Figures 15 and 16.

When the two windows are to be swung inwardly as for cleaning, the lower sash is first adjusted as shown in Figure 2. The upper sash is then pushed down until its top edge is free from the fixed guides 61 at which time the lower

edge is in engagement with the stops 70. The top of the sash is then pulled inwardly to swing the same, together with the guideways 66 on the pivots 67. As soon as the upper edge of the sash moves out of alignment with the fixed guides the lower ends of the links 74 will be swung on the pivots 76 a sufficient distance to cause them to enter the slots 77 so that the sash will thereupon be locked in the guideways 66 and will remain locked until it is again swung to vertical position.

The sash may also be provided with transverse weather strips in the usual manner and other window hardware provided such as the catch 78 for locking the sash in closed position. The various weather strip and guide members may be formed of extruded metal, rolled or made of sheet metal or in any desired manner to secure the shapes necessary for the various parts. It will also be noted that, while I have shown a double hung window, parts may also be utilized for single windows, and other changes may be made in the details of construction in order to adapt the invention to different windows, without departing from the scope thereof as set forth in the following claims, in which I claim:

1. The combination of a window frame having vertical channels therein, combined weather strips and guideway members at the sides of the frame, links connecting the lower portions of said members with the frame, slides movable in said channels, counter-balances connected with the slides, links connecting the slides with said members adjacent to the first-named links, pins on the sides of the sash which engage with the channels for guiding the sash in its vertical movement, and means for holding the pins in said channels at times, said means also being adjustable to permit the pins to be disengaged from the frame whereby the sash may be swung on said links.

2. A device as per claim 1 in which the means for controlling the pins comprises blocks in the sides of the frame having grooves to permit the passage of the pins, keepers mounted transversely of the blocks, springs for urging said keepers to innermost position to close the channels, said keepers having projections to close the inner ends of the slots when in retracted positions, catches pivoted on the outsides of the blocks and serving to close the outer ends of the slots when swung to one position and also serving to engage with the keepers to hold them in retracted positions.

3. The combination with a window frame having channels therein, of combined weather strip and guideway members at the lower ends of said channels, links connecting the lower portions of said members to the frame to provide pivotal and swinging engagement of said members with respect to the frame, a sash having grooves in the sides for slidable engagement with said members, slides mounted in said channels, links connecting the slides with said members above said first-named links, counterbalances connected with said slides, pins on the sides of the sash which engage with said channels for guiding the sash in its vertical movement, grooves at the sides of the sash to permit the pins to be disengaged from the channels to swing the sash on said links, and adjustable means for fastening the pins in the channels and permitting them to be disengaged from the channels.

4. In a window of the character set forth, the combination of a frame, stationary channel

shaped guideway and weather strip members extending from the top of the frame to approximately the middle thereof, a sash having grooves for engagement with the legs of said channel shaped members, similar channel shaped members normally in alignment with said first-named members and having their lower ends pivoted to the sides of the frame, guideways in the frame, slides mounted in said guideways, links connecting the slides with the sides of the sash, counter-balances having ribbons connected with said slides, the lower ends of said links extending beyond their pivotal connections with the sash and adapted to engage with slots in the legs of said last-named channel shaped members, the arrangement being such that the window may be slid downwardly to engage with said last-named channel shaped members and then swung inwardly with said last-named channel shaped members whereupon the ends of the links will engage with the slots to hold the sash in fixed position with respect to said pivoted members.

5. In a window, the combination of a frame, fixed guide members extending downwardly from the top of the frame, pivoted guide members normally in alignment with said fixed members and extending to the lower portion of the frame, means for pivotally connecting the lower ends of said pivoted guide members with the frame, a window sash slidably engaging with said guideways and normally held in sliding position, said window being adapted to swing with the lower pivoted guide members when in lowermost position and means for automatically locking the sash to said pivoted guide members when the sash is swung out of sliding position.

6. In a window, the combination of a frame including parting strips, channel-shaped weather strips having longitudinal blades positioned along the sides of the frame, a sash having grooves for receiving the legs of said weather strips to provide slidable engagement therewith, fixed weather strip members secured to the parting strips and having slots for receiving said blades, links connecting the lower ends of the first-named weather strips to the lower ends of the fixed weather strip members, and pivots secured to the lower edges of the sash and slidably engaging with the frame to permit the sliding and swinging movement of the sash, the arrangement being such that said channel-shaped weather strips and said fixed weather strip members will engage when the window is in closed position to make a tight closure between the frame and the sash.

55. 7. In a double hung window of the character set forth, the combination of a frame, stationary channel-shaped guideway and weather strip members extending from the top of the frame to approximately the middle thereof, a sash having grooves for engagement with the legs of said channel-shaped members, similar channel-shaped members normally in alignment with said first-named members and having their lower ends pivoted to the sides of the frame, guideways in the frame, slidable members mounted in said guideways, links connecting the slidable members with the sides of the sash, counterbalance means coacting with said slidable members for counterbalancing the sash in all positions, means at the lower ends of said links adapted to engage with the legs of said last-named channel-shaped members to hold the sash in fixed position with respect to the pivoted members when the sash is swung inwardly.
